Fig. 1

Fig. 3

Fig. 2

Fig. 4

FIG. 1 is a perspective view of the desk or table top air purifier showing the embodiment of my new design;
FIG. 2 is a front view of the air purifier;
FIG. 3 is a right side view; and
FIG. 4 is a top view.

The left hand view is a mirror image of the right hand view and the back is flat and unadorned.

The surface perforations are partially shown on the front filter element in FIGS. 1, 2 and 4 for convenience of illustration and are understood to be continuous on said surface.

I claim:

The ornamental design for a desk or table top air purifier, as shown and described.
